US00D458549S

(12) **United States Design Patent** (10) Patent No.: **US D458,549 S**
Roelke et al. (45) Date of Patent: ** Jun. 11, 2002

(54) **DIGITAL READOUT**

(75) Inventors: **Richard R. Roelke**, Bedford, NH (US);
Tina Hilbert, Hamburg (DE); **Gerd Schmieta**, Boston, MA (US)

(73) Assignee: **Metronics, Inc.**, Bedford, NH (US)

(**) Term: **14 Years**

(21) Appl. No.: **29/139,345**

(22) Filed: **Mar. 28, 2001**

(51) LOC (7) Cl. **10-04**

(52) U.S. Cl. **D10/65**; D10/46

(58) Field of Search D10/46, 65; D14/375;
345/87, 905, 794, 361, 681; 361/379, 383,
386

(57) **CLAIM**

The ornamental design for a digital readout, as shown and described.

DESCRIPTION

FIG. 1 is a front perspective view of the digital readout angled to the right according to this invention;

FIG. 2 is a front perspective view of the digital readout angled to the left according to this invention;

FIG. 3 is a front view of the digital readout according to this invention;

FIG. 4 is a rear perspective view of the digital readout angled to the left according to this invention;

FIG. 5 is a rear perspective view of the digital readout angled to the right according to this invention;

FIG. 6 is a rear view of the digital readout according to this invention;

FIG. 7 is a perspective right side view of the digital readout angled to the left according to this invention;

FIG. 8 is a perspective right side view of the digital readout angled to the right according to this invention;

FIG. 9 is a perspective left side view of the digital readout angled to the left according to this invention;

FIG. 10 is a perspective left side view of the digital readout angled to the right according to this invention;

FIG. 11 is a top perspective view of the digital readout angled to the left according to this invention;

FIG. 12 is a top perspective view of the digital readout angled to the right according to this invention;

FIG. 13 is a bottom perspective view of the digital readout according to this invention; and,

FIG. 14 is another bottom perspective view of the digital readout according to this invention.
